DESIGN FOR A PORTABLE RECORDER

Richard G. Leitner and William K. Rieber, West Los Angeles, Calif., assignors to Frank Rieber, Inc., West Los Angeles, Calif., a corporation of California

Application March 29, 1943, Serial No. 109,852

Term of patent 7 years

To all whom it may concern:

Be it known that we, Richard G. Leitner and William K. Rieber, citizens of the United States of America, residing in West Los Angeles, in the county of Los Angeles, State of California, have invented jointly a new, original, and ornamental Design for a Portable Recorder, of which the following is a specification, reference being had to the accompanying drawing, forming a part thereof.

Fig. 1 is a perspective view of a portable recorder showing my new design and showing the top, front and one side thereof;

Fig. 2 is a side elevational view of the recorder; and

Fig. 3 is a top plan view of the same.

We claim:

The ornamental design for a portable recorder, as shown.

RICHARD G. LEITNER.
WILLIAM K. RIEBER.
